UNITED STATES PATENT OFFICE.

ROBERT J. ZERBAN, JR., OF BELLEVILLE, ILLINOIS.

TRACTION-ENGINE.

SPECIFICATION forming part of Letters Patent No. 611,166, dated September 20, 1898.

Application filed April 27, 1898. Serial No. 679,023. (No model.)

To all whom it may concern:

Be it known that I, ROBERT J. ZERBAN, Jr., of Belleville, in the county of St. Clair and State of Illinois, have invented a new and Improved Traction-Engine, of which the following is a full, clear, and exact description.

The object of the invention is to provide a new and improved traction-engine arranged in such a manner that the principal weight—the boiler—hangs in springs, the driving-gear is in proper mesh at all times, and friction of the various parts is reduced to a minimum.

The invention consists of novel features and parts and combinations of the same, as will be described hereinafter and then pointed out in the claims.

Reference is to be had to the accompanying drawings, forming a part of this specification, in which similar characters of reference indicate corresponding parts in all the figures.

Figure 1 is a side elevation of the improvement, with parts broken out. Fig. 2 is a sectional side elevation of part of the improvement on the line 2 2 of Fig. 3, showing the rear support for the boiler. Fig. 3 is a plan view of the same, with parts in section. Fig. 4 is an end elevation of the front end of the improvement, with part removed. Fig. 5 is a plan view of the front axle-sleeve. Fig. 6 is a side elevation of the same, and Fig. 7 is an inverted plan view of a king-bolt plate.

The boiler A of the traction-engine is provided forward of the fire-box A' with bearings B, in which is mounted to turn the transversely-extending middle part C of a U-shaped axle-frame having side arms C' C² extending rearwardly on the sides of the fire-box to carry at their free ends the alined spindles D D', respectively, on which are mounted to rotate loosely the rear or traction wheels E E'. The free ends of said arms C' C² are yieldingly connected with the fire-box A' of the boiler by means of springs F F', of which the springs F are held on lugs C³ and are engaged at their upper ends by lugs on plates G, riveted or otherwise fastened to the sides of the fire-box A'. The springs F' are held on the outermost ends of said arms C' C² and are engaged at their upper ends by washers carried by links G', pivotally connected with plates G², likewise secured to the sides of the fire-box A'.

Now it will be seen that by the arrangement described the axle-frame is free to swing with the middle portion C as the pivot, and as the connection between the side arms and the boiler A is yielding by means of the springs F F' it is evident that any up-and-down movement of the boiler will be taken up by the springs F F', the frame being free to swing upward or downward with the boiler as the fulcrum for the middle portion C and with the traction-wheels E E' as the fulcrum for the frame at the spindles D D'. The middle portion C of the axle-frame is made hollow to form a bearing for a transversely-extending shaft H, carrying at its ends pinions H' in mesh with gear-wheels E², secured to the traction-wheels E E'.

Now it is evident that no matter which way the boiler A moves relative to the traction-wheels E E' the pinions always remain in proper mesh with the gear-wheels E², so that no binding whatever takes place between the gearing mentioned, and a proper transmission of power takes place from the shaft H to the traction-wheels. The shaft H is connected at the side arms C² by a differential gearing with a gear-wheel J, mounted to rotate loosely on the shaft H, and in mesh with a gear-wheel J', mounted to rotate loosely on a stud J², secured to the boiler A. The gear-wheel J' is in mesh with a pinion J³, secured on a crank-shaft J⁴, connected in the usual manner with the engine K, carried on the forward end of the boiler A.

When the engine is set in motion, a rotary motion is given to the shaft J⁴, so that the pinion J³ rotates the gear-wheel J' and the latter the gear-wheel J, so that by the differential gearing I a rotary motion is given to the shaft H and the pinions H' to rotate the gear-wheels E², and consequently the traction-wheels E E', to propel the engine forward or backward, according to the direction in which the shaft J⁴ is turned. The differential gearing I may be of any approved construction—such as indicated, for instance, in Fig. 3, in which the pinions I' are journaled in the web of the gear-wheel J and roll off on a bevel gear-wheel I², secured on the side arm C² of the frame C, the pinions I' being also in mesh with a bevel gear-wheel I³, secured on the shaft H.

The front axle of the traction-engine is made in two parts L L', on which are journaled the front wheels N N', respectively. The shafts L L' are secured in a sectional sleeve O, having its two parts O' O² fastened together by suitable bolts O³, as is plainly indicated in Figs. 4, 5, and 6. The middle of the sleeve O is formed with an inclined opening O⁴ for the passage of the lower end 5 of the king-bolt P, secured at its upper end to a casting P', bolted or otherwise fastened to the under side of the boiler A at the forward end thereof. The top of the sleeve O is provided with a bearing O⁵, into which opens 10 the opening O⁴, and the said bearing is provided at the front and rear with alined recesses O⁶, in which are seated the lugs Q', formed on the king-bolt plate Q, held loosely 15 on the king-bolt P. On the top of the plate Q rests the lower end of a spring R, abutting 20 with its upper end against the casting P'.

Now it will be seen that by the arrangement described the king-bolt Q is free to rock on the sleeve O when the axle assumes an inclined position, as indicated in Fig. 4, the 25 plate Q always standing in proper position relative to the vertically-disposed king-bolt P, so that the boiler A remains in vertical position even should the wheels N N' assume inclined positions, as shown in Fig. 4.

The draw-bar T is pivotally connected with the side arms C' C² of the axle-frame, as shown in Figs. 1, 2, and 3.

Having thus fully described my invention, 30 I claim as new and desire to secure by Letters Patent—

1. A traction-engine, provided with a boiler, an axle-frame approximately U-shaped, and

fulcrumed at its middle portion on the boiler, and carrying at its ends alined spindles for 40 the traction or rear wheels, and springs interposed between the boiler and the frame at the spindles, substantially as shown and described.

2. A traction-engine, provided with a boiler, 45 an axle-frame approximately U-shaped, and fulcrumed at its middle portion on the boiler, and carrying at its ends alined spindles for the traction or rear wheels, springs interposed between the boiler and the frame at the spindles, a counter-shaft carried by the pivot portion of said axle-frame, intermeshing gears upon the counter-shaft and traction-wheels and connections from the counter-shaft to the engine, substantially as shown and described. 50

3. The combination of an axle, comprising a two-part sleeve having a vertical and longitudinal slot therein, means for clamping the two parts together, and wheel-journals held within the ends of the sleeve, with a 60 king-bolt entering the slot, and a plate surrounding the king-bolt and having central ribs engaging the upper surface of the sleeve, substantially as shown and described.

4. A traction-engine, provided with a boiler 65 carrying a king-bolt, a sleeve carried by the front axle, a king-bolt plate on the king-bolt, and seated to rock on the bearing of said sleeve, and a spring on the king-bolt and interposed between the bolt and the king-bolt 70 casting, substantially as shown and described.
